A. WEBER

TOY AEROPLANE

Filed Aug. 17, 1922

INVENTOR.
AUGUST WEBER.

BY

Richard D. O'wey
ATTORNEY

UNITED STATES PATENT OFFICE.

AUGUST WEBER, OF JERSEY CITY HEIGHTS, NEW JERSEY.

TOY AEROPLANE.

Application filed August 17, 1922. Serial No. 582,480.

To all whom it may concern:

Be it known that I, AUGUST WEBER, a citizen of the United States, residing at Jersey City Heights, in the county of Hudson and State of New Jersey, have invented certain new and useful Improvements in Toy Aeroplanes, of which the following is a specification.

This invention relates to a toy and has for its principal object to provide a structure imitating an aeroplane and including means whereby the same may be sailed in the air and a noise made similar to that of a motor of an aeroplane.

Another important object of the invention is to produce a toy of this nature which may be manufactured at a comparatively low cost, which will be extremely amusing and which will be harmless and afford excellent exercise to the operator thereof.

With the above and numerous other objects in view as will appear as the description progresses, the invention resides in certain novel features of construction, and the combination and arrangement of parts as will be hereinafter more fully explained.

In the drawings,

Figure 1 is a plan view showing the blank from which the body of the toy is formed.

Figure 2 is a vertical longitudinal section through the forward portion of the toy.

Figure 3 is an elevation of one cam member used in conjunction with the toy.

Figure 4 is a longitudinal section through the noise making apparatus.

Figure 5 is a perspective of the toy assembled.

Referring to the drawings in detail, it will be seen that the body 1 is formed from a blank such as is disclosed in Figure 1 and by folding the same along the dotted lines *a*, *b*, *c*, placing the tab 2 through the slot 3, the body may be assembled. The rear end of the body is pointed, the body tapering toward its rear end. The forward end is closed by the flap 4, the tab 5, thereof being bent so that its apertures 5^a registers with the aperture 6 so that any suitable device, such as a peg may be passed therethrough for holding the body together.

The flap 7 with the flaps 8 and 9 form an extension boxing 10 at the forward end of

the body, the aperture 10 registering with the aperture 11 so that a sleeve 12 may be extended therethrough as is illustrated in Figure 2. The tabs 13 of the flap 7 are adapted to receive the slot 14 in the tabs 8 and 9 while the tab 15 engages the slot 16. The wings 17 are attached transversely on the upper side of the body when thus folded, by having its slot 18 engage the tabs 19 and suitable means may be passed through the apertures thereof for holding the wing in place. The tail portion 20 is suitably attached to the body on the upper side thereof and at its rear end. A string 21 is passed through the aperture 22 of the body 1 and is preferably attached at its other end to a stick 22^a so that the body may be readily sailed through the air by rotating the end of the stick 75 in a circle.

Coming now to the noise making feature of the toy, it is to be noted that the sleeve 12, previously mentioned, is provided at its forward end with a curved cam-shaped formation indicated at 23 which may be more specifically described as a ratchet clutch formation. A shaft 24 is slidable and rotatable in this sleeve 12 and at its rear end is provided with a washer 25^a or some such other similar stopping means preventing the accidental removal of the shaft 25 as it is thrown forwardly as will be more evident as the description progresses. A cam member 25 is keyed to the outer end of the shaft 24 and is in the form of a sleeve having an inner end 26 similar to the end 23 and adapted to co-act therewith. A suitable propeller 27 is mounted on this shaft 24 at its end being suitably keyed thereto so as to rotate therewith. It will thus be seen that as the body of the toy is moved in a forward direction, it will cause the rotation of the propeller 27 and because of the cam ends 23 and 26 there will be a reciprocatory motion imparted to the shaft 25 and as the ends come together there will be a noise which noise is similar to the noise made by an ordinary internal combustion engine such as is used upon aeroplanes.

It is thought that the construction and operation of the invention will now be readily understood without a more detailed description thereof, but it is desired to point out that I have merely disclosed the present embodiment of my invention by way of

example and that numerous changes in the details of construction and combination and arrangement of parts may be resorted to without departing from the spirit of the invention as hereinafter claimed.

Having thus described my invention what I now claim as new and desire to secure by United States Letters Patent is:—

1. In a toy aeroplane comprising a body, a sleeve carried by the body having a cam surface at its forward end, a rotatable and slidable shaft in the sleeve, a cam member mounted on the said shaft cooperating with the cam surface of said sleeve, and
- 10 a propeller rotatable with the shaft whereby noise is produced as the cam surface and cam member engage each other.
- 15

2. In a toy aeroplane comprising a body formed from a single blank having a forward extension, a sleeve supported by said extension and fastened within the body, a cam surface on the forward end of the sleeve, a shaft having a combined propeller and a cam rotatable therewith, said cam surface and cam intermittently engageable whereby a noise is produced upon the rotation of the said propeller.

In testimony whereof I affix my signature in the presence of two witnesses.

AUGUST WEBER. [L. S.]
